MECHANISM FOR HANDLING AND ELEVATING DISCRETE MATERIAL

Walter H. Bullwinkle, Fairbanks, Territory of Alaska

Application February 19, 1951, Serial No. 211,727

9 Claims. (Cl. 214—130)

1

This invention relates to improvements in a mechanism for handling and elevating discrete material and, more particularly, has to do with material handling machinery for elevating material pushed to an elevator mechanism at ground level for elevation thereabove for disposal and powered by the means whereby the material is pushed.

There are many occasions in the handling of discrete materials such as earth, gravel, grain and the like in which it is desired to elevate the same. A typical example of such a situation arises in a gravel-handling operation wherein the gravel is to be screened and washed between an elevated level above the ground and a lower discharge or disposal point and the size and volume of the operation is such that it is uneconomical to supply a power means for performing the elevating operation separate and apart from the power means whereby the gravel is brought or moved to the elevator means. A placer mining operation is such a situation especially where gravel is being bulldozed from the earth's surface and conveyed to a grizzly and flume where it is screened of the larger boulders and then washed in the flume. Normally such a grizzly is located at the highest end of the flume and the gravel is deposited thereon whereupon the finer components pass down through the grizzly grid. Often such flumes are fed by means of clamshell buckets, power shovels, or draglines but in each instance if the material being treated must be conveyed any distance a bulldozer likewise has to be used.

It is therefore among the important objects of this invention to provide, for use with a grizzly and flume in such an operation, an elevator means for raising material from a ground level delivery point to the elevated grizzly which is so arranged that it may be actuated by a bulldozer during the latter's withdrawal from making gravel delivery; that is attachable and detachable from the actuating unit automatically as the unit moves toward and away from the elevator means; that is simple to construct and operate and requires a minimum of personnel to provide effective handling of large quantities of material; and which is very mobile. These and other objects of the invention will become more apparent during the course of the following specification in which is described the preferred forms of the invention as shown in the accompanying drawings, in which:

Figures 1 through 4 show schematically a typical discrete material handling operation and the

essential components and operations of my mechanism;

Figure 5 is a perspective view of the elevator scoop and its pivotal rocker arms and the cable actuation means therefor;

Figure 6 is an enlarged perspective view of an automatically engageable hook of an earthmover for cooperation with the cable actuation means;

Figure 7 is a perspective view of cable guide means used in my mechanism;

Figure 8 is a fragmentary perspective view of a resilient cable anchor employed in connection with the rockers of the scoop;

Figures 9 and 10 are fragmentary vertical sections of a portion of the bulldozer blade showing the automatically engageable hook of Figure 6 in its two positions; and

Figures 11 and 12 are schematic views detailing the action of the scoop during elevation and descent in the raising of a quantity of material.

Referring particularly to Figures 1 through 4, I have shown a track-laying or crawler type tractor 20 having the usual pusher arms 22 extending forwardly on each side thereof and connected to the bulldozer blade 24 by means of which a quantity of discrete material, such as gravel 26, may be pushed toward the elevator mechanism. The latter comprises the skid timbers 28 that are normally used in pairs to support the operating mechanism and to facilitate dragging the machine from place to place. Columns 30 and 32, used in pairs, support at an elevated level the grizzly frame 34 to which gravel 26 is to be delivered. A foreframe is also provided on the skids 28 and comprises the upright columns 36 in pairs and which are suitably braced and buttressed in advance of scoop 40. The foreframe is open in front of the scoop to permit, as shown in Figure 2, the partial entry of the earthmover 20 and particularly the pusher or bulldozer blade thereof.

The delivery of gravel to the scoop 40 is accomplished by forming a pile of it in advance of the blade 24 and then pushing it into the scoop when the latter is down in its lowermost position such as is more fully shown in Figure 5. In this position the scoop has one wall disposed to lie on the ground so that the mouth of the device is open to receive the gravel or the like. The scoop has an arm 42 at each end which is pivotally connected to a column 30 to swing about the axis 44. To the rear of said axis there is provided on each arm a rocker element 46 by which the scoop is swung from the lower to the upper position through the instrumen-

tality of the actuation cable 48 that comprises a U-shaped flexible line suitably supported and arranged in the foreframe and anchored at each end to a rocker element. The cable 48 includes the bight 50 disposed across the foreframe in front of scoop 40 and the ends 51, 51 which pass around guide sheaves 52, 52 over counterbalanced guide blocks 54, 54 thence around the perimeters of the rocker elements 46 where the ends are anchored either rigidly as shown in Figure 5 or resiliently as in Figure 8.

It will be seen that when cable bight 50 is pulled outward between guides 52, power will be applied to the rocker elements to cause them to revolve about their axes whereupon the scoop 40 between arms 42 will be elevated from the lower position shown in Figures 1 and 2 to the intermediate and upper material-delivering positions shown in Figures 3 and 4 respectively. In the latter position the scoop is inverted and material that has been contained therein will be dumped upon the grizzly which then underlies it.

To facilitate the operation of the scoop during elevation its action is articulated by the use of a flexible or extensible link between the lower rear of the scoop and the grizzly frame. The link is best shown in Figure 12 to comprise piston rod 58 pivotally connected at 60 to the scoop and cylinder 62 pivotally connected at 64 to a cross member 66 extending laterally between two uprights 30. The pivot 64 is lower than axis 44. It is arranged so that the piston 59 within cylinder 60 is fitted tightly and the expansible-contractible chambers on each side of it are ported to the atmosphere so that the link extends freely but contracts slowly. Thus, when the scoop is being raised the link merely extends and acts to hold the scoop 40 in its desired earth-containing position until it is dumped and permitted to descend. At that instant the slow contraction of the link takes over and the descent of the scoop is cushioned as it approaches the ground level.

The action of the extensible-contractible link upon the pivoted scoop is shown in both the ascending and descending paths indicated in Figure 11 by upward and downward directed arrows. The lowermost dotted line showing A of the scoop 40 indicates its position on the ascent and its uppermost dotted line position B indicates its disposition as it nears the ground. Arrow-headed lines a—a and b—b indicate, respectively, the path and disposition of the scoop in its two directions of travel. It will be noted that in this latter situation the scoop 40 is pivotally mounted at its ends on pins 41 between arms 42, 42. However, in those cases where there is no need to cushion the fall of the scoop to the ground or its cushion may be had in another way, the joiner of the scoop and the arms need not be pivotal but may be solid as a shovel blade is joined to its lever. This latter condition is disclosed in Figures 1-4.

It has been mentioned that the tractor engages the hoisting cable 50. This is accomplished by means of the forwardly open, U-shaped hook 70 shown in Figures 6, 9 and 10 as mounted upon scraper blade 24. Normally such blades have an upper ledge or flange 25 provided as part of their strengthening means upon which is mounted an upstanding L-shaped bracket 72 that constitutes the pivotal mount for hook 70. The hook is joined to the bracket by hinge 71 intermediate its throat and the outer end of one of its legs. During forward motion of the car-

rier blade the hook is disposed as in Figure 9 and receives the cable 50 across its mouth. As the hook advances the cable passes to the throat or crotch of the hook whereupon it is overthrown and the cable is placed behind and beneath the pivotal connection between hook and bracket support. When the direction of the hook is reversed, as when the earthmover withdraws, a pull is exerted upon the cable which, being the bight of the line that actuates the rockers 46 causes them to swing and the scoop 40 to be elevated to dumping position.

Disengagement of line 50 from the hook 70 is had by means of a trip line 76 which is similarly disposed across the front of the frame in advance of scoop 40 but at a slightly higher level than that of line 50. The trip line 76 is guided by blocks 78, 78, tensioned by blocks 80, 80 and connected to the rockers 46 all in a manner similar to the hauling line. Note however that line 76 has a stop 82 on each of its standing parts. Such stops are so located that they come into abutment with the wall 84 around hole 86 through which the line passes to sheave 78. Thus, when the hook 70 is overturned on the inward passage of the pusher blade of the earthmover the upper arm of the hook sweeps through an arc that encompasses line 76 and places it in the tripping position shown in Figure 10. As the tractor withdraws the trip line operates to return the hook to its normal position when the stops 82 come against wall 84 which prevents further paying out of the line 76. As soon as the hook is turned back to its usual disposition the line 50 is freed and the descent of the scoop may begin. The earthmover of course merely continues on rearward or turns or is manipulated so as to gather to its blade a next quantity of earth to be loaded into the scoop.

Hook 70 preferably has a broad bottom lip 71 which carries through the throat at least and is then shaped to provide an upper strong horn behind which the trip line comes to rest. Broadening the contact lip and throat reduces wear on the cable and improves the entrance action of the cable into the hook as the tractor moves forward.

For the purposes of taking up slack in the hoisting and trip lines 50 and 76, the blocks 54, 54 and 80, 80 are attached to suspension lines 90, have counterweights 92 attached to their ends, and are passed over sheaves 94. When no substantial pull is exerted on the hoisting and trip lines their slack is taken up by descent of the counterweights which tend to bend the standing parts of the lines as shown in Figure 5. Of course, when a pull is applied to the lines the bend is removed and the taut lines immediately move with the force applied thereto.

The rockers 46 are preferably formed as castings although they can easily be fabricated from bar stock and welded together in the openwork manner shown. In one segment of the rocker which is uppermost when the scoop is at ground level I have filled the opening by casting therein a counterweight 47 of concrete which tends to aid the ascent of the scoop and tends to counterbalance its return to the lower position after dumping.

In Figure 8, where the hoisting and trip lines are shown as resiliently anchored to the rockers 46, the lines pass over sheaves 82, through a guide clip 83 and have at their ends, respectively, springs 51 and 77 which are in turn anchored to brackets 53 and 79 on the rocker. The springs

are extremely strong and are employed primarily to impart a slight give to the lines to prevent their snapping in the event that a sharp application of force is applied for one reason or another.

A typical elevating operation is as follows: the earthmover pushes its load of material forward of it and into the foreframe 36 of the machine until it is deposited in scoop 40. As the tractor enters the foreframe the forwardly open hook 10 engages the hoisting line and in the course of further movement is tipped over to the position of Figures 6 and 10. At the same time the trip line has been disposed behind the upper horn of a hook as shown in Figure 10. It is arranged that the slack in the lines be sufficient that, taken with the resiliency imparted through springs 77, 51, the earthmover can enter sufficiently to deposit its load but not to tend to elevate the scoop above the ground. When the load has been deposited the operator reverses the direction of travel of the tractor and it withdraws from the foreframe and tightens the cables, and, primarily, imparts a draft on line 50 to cause the rockers to revolve about their axes elevating the scoop 40 to the dumping position. At the same time line 76 is tensioned and has the boss 82 so arranged thereon that when the scoop has been raised and the tractor has withdrawn a predetermined distance, boss 82 comes into contact with cheek plate 84 of the housing for the guide sheaves 78 whereupon further withdrawal of the trip line is precluded. Thereupon the trip line comes into play and causes an overturning movement on hook 10 to return it to the position of Figure 9 which permits the hoisting line to come free and the tractor to release the scoop to return to its down position.

While I have shown and described my invention as embodied in particular constructions it will be apparent to those skilled in the art that modifications and changes may be made within normal skill without departing from the spirit and scope of the invention as more fully defined in the subjoined claims.

I claim:

1. A machine for handling discrete material and for elevating it from a ground level delivery to an upper discharge point, comprising: a frame in which said material is to be elevated including a first pair of upright columns and a second pair of upright columns positioned in advance of the said first pair; an arcuate rocker pivotally mounted at its axis to each of said columns of the first pair; each said rocker having a rigid arm projecting radially from one end of the arc thereof; an elongated scoop supportedly mounted at each end on one of said rocker arms and ranged to receive material shoved thereto when said rocker arms are in depending position; a cable anchored at each end to one of said rockers at that end of the arc that is opposite the location of the rigid arm thereof; said cable being guidedly supported by said second pair of upright columns and extending therebetween to locate a bight of the cable in advance of said scoop; a self-powered vehicle to push material into said scoop when the same is in the material-receiving position; and an upstanding horn on said vehicle to engage and pull upon said cable bight when the vehicle is withdrawing from the scoop to impart a draft on the cable and its ends and actuate the rockers and their arms to produce elevational motion of the scoop to the upper discharge point.

2. A machine for handling discrete material

75

and for elevating it from a ground level material-receiving point to an upper discharge point, comprising: scoop means for receiving material shoved thereto at ground level; a frame about said scoop means for movably locating the same; means mounted in said frame and operably associated with said scoop means for guiding the same during its movement from ground level to the upper position; a cable including a bight and guidedly associated with said scoop means for raising the same; said cable bight being positioned in said frame in advance of the scoop means while the same is in material-receiving position; a vehicle adapted for shoving material to said scoop means; and a forwardly open U-shaped, hook on said vehicle to engage the cable bight on forward movement of said vehicle; said hook being pivotally mounted on said vehicle in such manner that the hook tilts upright when the cable is in the gullet thereof causing the cable to be disposed behind and below said pivotal mount whereby withdrawal of the vehicle imparts a draft upon the cable and a raising of the scoop means within said frame to the material discharge position.

3. A machine for handling discrete material and for elevating it from a ground level material-receiving point to an upper discharge point, comprising: scoop means for receiving material shoved thereto at ground level; a frame about said scoop means for movably locating the same; means mounted in said frame and operably associated with said scoop means for guiding the same during its movement from ground level to the upper position; a cable including a bight and guidedly associated with said scoop means for raising the same; said cable being positioned in said frame in advance of the scoop means while the same is in material-receiving position; a vehicle adapted for shoving material to said scoop means; a forwardly open, U-shaped, hook on said vehicle to engage the cable bight on forward movement of said vehicle; said hook being pivotally mounted on said vehicle in such manner that the hook tilts upright when the cable is in the gullet thereof causing the cable to be disposed behind and below said pivotal mount whereby withdrawal of the vehicle imparts a draft upon the cable and a raising of the scoop means within said frame to the material discharge position; a second extensible trip line having a bight overlying said cable bight in a position to be engaged behind the upper arm of said U-shaped hook when the latter is tilted upright; and stop means to limit extension of said trip line on withdrawing motion of the vehicle to retilt said hook to its normal, forwardly open position.

4. The structure according to claim 3 in which the stop means for trip line comprises a ferrule on the stop line and abutment means is provided to be engaged by said ferrule whereby the withdrawing motion of the trip is arrested.

5. A mechanism for handling discrete material and for elevating it from a ground level delivery to an upper discharge point, comprising: a frame in which said material is to be elevated; a pairs of arms each pivotally mounted at one end in said frame in a coaxial manner and supporting therebetween spaced from the pivotal mounts a scoop to travel in an arcuate path between a ground level material-receiving position and an elevated material-discharging position; a rocker element associated with each arm of the scoop; a cable anchored at each end to one

of said rocker elements to effect simultaneous revolving of said rockers, said cable having a bight horizontally disposed across said frame in front of said scoop; a self-powered vehicle to push material into said scoop when the same is in the material-receiving position; and an upstanding horn on said vehicle to engage and pull upon said cable bight when said vehicle is withdrawing from the scoop to impart a draft on said cable ends to revolve said rockers and thereby elevate said scoop to an upper material-discharging position.

6. The structure according to claim 5 in which the scoop is pivotally mounted at each end to one of said arms and an extensible pivotally-connected buffer link is disposed between a lower point on said scoop and said frame below the pivotal axis of the said arms.

7. The structure according to claim 5 in which the means on the vehicle to engage the cable bight is a forwardly open, U-shaped, pivotally-mounted hook that engages the cable bight on forward movement of the vehicle, said hook having its pivot mounting arranged so that the hook tilts upright when the cable is pressed into the gullet thereof causing the cable to be disposed behind and below the pivot mount.

8. The structure according to claim 5 in which the vehicle has a bulldozer blade on its forward end and which blade supports a horn that in turn has pivotally coupled thereto a forwardly open, U-shaped, hook that engages the cable bight on forward movement of the vehicle and which hook is pivotally coupled to said horn at one side so that when the cable is in the gullet of the hook 35

the latter tilts upright causing the cable to be disposed behind the horn and below the pivot mount of said hook.

9. A mechanism for handling discrete material and for elevating it from a ground level delivery to an upper discharge point, comprising: a frame in which said material is to be elevated; a scoop movably mounted in said frame in a manner to move in an arcuate path between ground level and the upper discharge point; cable actuated means associated with said scoop to produce such movement; and a cable bight connected to said cable actuated means and horizontally disposed across said frame in front of the scoop; a self-powered vehicle to push material into said scoop when the same is in the material receiving position; and an upstanding horn on said vehicle to engage and pull upon said cable bight when the vehicle is withdrawing from said scoop to impart a draft on the cable and actuate the means associated with the scoop to produce elevational motion of the same.
